UNITED STATES PATENT OFFICE.

LEW ARNTZ, OF DES MOINES, IOWA.

BUTTON STRUCTURE.

Application filed November 18, 1922. Serial No. 601,849.

To all whom it may concern:

Be it known that I, LEW ARNTZ, a citizen of the United States, and a resident of Des Moines, in the county of Polk and State of Iowa, have invented a certain new and useful Button Structure, of which the following is a specification.

The object of my invention is to provide a button structure of simple, durable, and 10 comparatively inexpensive construction.

More particularly, my invention relates to a button structure, which may be easily secured to any suitable material and which, when once placed in position, will become 15 permanently locked against undesired removal.

More particularly, my invention relates to a two-part button structure which when securely locked together, there will be no rotation of the parts except in one predetermined 20 position.

Still another object is to provide a peculiar type of button in which the parts may be quickly separated for removing it from 25 the material to which it is fastened.

With these and other objects in view, my invention consists in the construction, arrangement and combination of the various parts of my device, whereby the objects contemplated are attained, as hereinafter more 30 fully set forth, pointed out in my claim, and illustrated in the accompanying drawings, in which:

Figure 1 is a top plan view of the button.

Figure 2 is an inverted plan view of the front member of the button.

Figure 3 is a top view of the back member.

Figure 4 is a side elevation of the parts of the button connected together.

Figure 5 is a sectional view taken on line 5-5 showing the button connected to cloth.

Figure 6 is a sectional view of a slightly modified form of button; and

Figure 7 is a view similar to Figure 4 with the back member having a smooth face.

In the accompanying drawings, I have used the reference numeral 10 to indicate generally, the front member and 11 to indicate generally the back member of my button.

The front member 10 is provided with a hub or the like portion 12. The member

10 is provided with a central screw threaded opening 13 and the member 11 is provided with a central screw threaded member 14. The screw threaded members 13 and 14 are in alignment with each other and receive the screw 15.

On the adjacent faces of the front and back members 10 and 11, I provide coacting engaging parts 16 and 17. The coacting engaging parts 16 and 17 are preferably teeth, which may engage the cloth on each side. The coacting engaging parts are radially spaced from the screw threaded openings in the front and back member so as to form a recess within the ring formed by the teeth or coacting parts. The screw 15 extends through the cloth 18 and connects the front and back members 10 and 11 together.

It will be seen that the member 11 may be rotated in the direction indicated by the arrow 19 for locking it in position. The fact that the coacting teeth 16 and 17 will engage on each side of the cloth, will prevent any rotation of the back 11 in the direction opposite from that shown by the arrow 19.

When it is desired to remove the button, all that is necessary is to unscrew the screw 15. My button is very practical for use on overcoats and other heavy materials, but will work successfully on all kinds of cloth.

In Figure 6 of the drawings, I have shown a slightly modified form of button in which the front member is composed of the two parts 20 and 21. The part 20 may be made of shell or any other suitable material, and is connected to the part 21 by having in-turned flanges 22 on the member 21, which extend into a groove 23 formed in the member 20.

The parts just described are clearly shown in Figure 6 of the drawings.

The part 21 is provided with a screw threaded stem 24. A back member 25, similar in construction to the member 11 is used for engaging the stem 24. The part 21 is provided with teeth 16 which are radially spaced from the stem or screw threaded member 24. The coacting parts for engaging the cloth 18, as shown, in Figure 6, are similar in construction to those shown in the rest of the drawings.

In the form of invention shown in Figure 6, it is impossible to remove the back member 25 when once placed in position, with-

out tearing the material on which the button is fastened. In Figure 7, I have shown the back member 11 with a smooth face, thereby providing a button having only one part provided with teeth or the like to engage the cloth. The smooth face may be put on the front member and roughened part on the back member if desired. This type can be removed from the cloth if desired without any injury to the cloth. It will be understood that the roughened parts may be made in various sizes for accomplishing the result desired.

It will be seen that my button may be easily and quickly fastened to cloth and, in view of the fact that it comprises a front and back member, will remain in position without danger of being completely torn away from the cloth.

20 Some changes may be made in the construction and arrangement of the various parts of my invention, without departing from the real spirit and purpose of my invention and it is my intention to cover by 25 my claim, any modified forms of structure

or use of mechanical equivalents, which may be reasonably included within its scope.

I claim as my invention:

A button structure of the class described including a front and a back member, said front member having a screw threaded stem thereon, teeth formed on one of the faces of said front member and spaced radially from said stem, said teeth extending upwardly from the face of the member on which they are mounted for forming a recess, said back member having a screw threaded opening therein for receiving said stem, teeth formed on one face of the back member for coacting with the teeth on the front member, said teeth being spaced radially from said opening and extending upwardly from the face of the member on which they are mounted for forming a recess, the material on which the button is fastened being engaged by said teeth at a point spaced from the point where the stem extends through the material as and for the purposes stated.

Des Moines, Iowa, September 29, 1922.

LEW ARNTZ.
